UNITED STATES PATENT OFFICE.

DANIEL CONBOY, OF TORONTO, ONTARIO, CANADA.

CARRIAGE-TOP SPRING.

SPECIFICATION forming part of Letters Patent No. 529,780, dated November 27, 1894.

Application filed February 26, 1894. Serial No. 501,535. (No model.) Patented in Canada February 5, 1894, No. 45,241.

To all whom it may concern:

Be it known that I, DANIEL CONBOY, of the city of Toronto, in the county of York and Province of Ontario, Canada, have invented 5 certain new and useful Improvements in Carriage-Top Springs, (for which I have obtained a patent in Canada, No. 45,241, bearing date February 5, 1894,) of which the following is a specification.

10 The object of the invention is to devise a simple and effective counterbalancing spring for carriage tops; and it consists, essentially, of a combined coiled and torsional spring located in front of the pivot of the vertical 15 brace and adapted to engage therewith by means of a hook integral with the said coil, substantially as hereinafter more particularly explained and then definitely claimed.

In the accompanying drawings, Figure 1, 20 is a perspective view of a carriage top provided with my improved spring. Fig. 2, is an enlarged perspective detail of the spring and its connections when the carriage top is raised. Fig. 3, is a similar view of the same parts 25 when the carriage top is lowered. Fig. 4, is a sectional elevation of the spring. Fig. 5, is an end elevation of the same.

Like letters of reference indicate corresponding parts in the different figures. 30 A, is the carriage seat rail, on the arm B, of which the vertical brace C, is pivoted. Located in front of the said arm is the spring D, constructed as hereinafter more particularly set forth. This spring is carried by 35 the bracket E, projecting from the arm B.

F, is a hook formed integral with the spring D, and engaging with the brace C, as shown.

On reference to Figs. 4 and 5, the arrangement of the spring D, will be readily understood.

G, is a sleeve connected to the bracket E. A portion b, of the spring D, runs through this sleeve and is held from turning by being bent and inserted in the recess a. After 45 emerging from the sleeve G, the spring coils back toward the starting point and finally terminates in the hook F, which engages with the brace C, as before described. From this arrangement of the spring, it will be seen that 50 every coil is available for the purpose of pro-

ducing a spring tension, and that further, the portion inside the sleeve G, acts as a torsional spring, the whole construction rendering a short spring as effective as a much longer spring of ordinary construction and connection. 55

From the location of the spring in front of the pivot point of the brace C, it follows that as the carriage top is lowered, the point at which the hook acts is shifted closer and closer 60 to the pivot point of the brace, and the leverage of the spring is thus decreased as its tension is increased, thus avoiding all tendency of the carriage top to jump when in its lowered position. (See Fig. 3.) This is a most important feature in my spring, as unless some such method is provided to compensate for the increased tension of the spring, other means must be provided to securely hold the top in its lowered position. 70

It will of course be understood that the spring D, and its connections are preferably duplicated at the other side of the top, thus forming a very perfect counterbalance for the weight of the top when the latter is being 75 raised or lowered.

In the drawings I show my improved spring applied to a buggy top, but it is of course equally as well adapted for use in phaeton tops, in which case the side rails are dispensed 80 with and the back rail made in two portions fastened to the back of the phaeton body at opposite sides.

I am aware that it is not new to use springs for the purpose of balancing carriage tops, 85 and therefore do not attempt to claim such broadly, but regard as important the position in which said springs are placed. It is new, so far as I know, to place the spring in such a position that as the top is lowered, the leverage of the spring is decreased, as said springs have heretofore been used in such a position that when the top was lowered, the tension of the spring was greatly increased, while the leverage remained the same, and this increase 90 tends to elevate the top instead of allowing it to stay in its lowered position. My improvement, on the contrary, does not have this disadvantage for the reason, as heretofore explained, that as the tension increases, the 95 100

leverage of the spring is decreased, because its acting part approaches nearer the pivot, thus avoiding all tendency of the carriage top to jump when in its lowered position.

5 What I claim as my invention is—

1. The combination in a carriage top and with the pivot thereof, of a coiled spring situated in front of said pivot and so arranged that its acting end will swing behind said pivot 10 when said top is lowered, whereby the leverage of said spring decreases as its tension increases, substantially as described.

2. In a carriage top, the sleeve G, in combination with the spring D, composed of a torsion part (b) connected at one end to the sleeve G, and extending through the same and of a coiled part arranged outside the said sleeve and terminating at or near the point of connection of the part b, in an arm engaging with the vertical brace C, substantially as and for the purpose specified.

nection of the part b, substantially as and for the purpose specified. 20

3. In a carriage top, the sleeve G, connected with the rail, in combination with the spring D, composed of a torsion part (b) connected at one end to the sleeve G, and extending through the same, and of a coiled part arranged outside the said sleeve and terminating at or near the point of connection of the part b, in an arm engaging with the vertical brace C, substantially as and for the purpose specified. 25

Toronto, February 23, 1894.

DANIEL CONBOY.
